United States Patent Office

Des. 204,666
Patented May 10, 1966

204,666

BUILDING

Robert J. Crawford, 7019 Altair Parkway, Sacramento,
Calif., and Bryan H. Oldfield, Citrus Heights, Calif.

Filed Oct. 19, 1965, Ser. No. 87,603

Term of patent 14 years

(Cl. D13—1)

FIG-5

FIGURE 4 is a front elevational view of the other end; and,

We claim:

The ornamental design for a building, as shown.
